UNITED STATES PATENT OFFICE.

IVAR WIDING, OF DORCHESTER, MASSACHUSETTS, ASSIGNOR TO NINA M. PORTER.

CEMENT SHIP CONSTRUCTION.

1,353,880.

Specification of Letters Patent. Patented Sept. 28, 1920.

Application filed July 20, 1917. Serial No. 181,685.

To all whom it may concern:

Be it known that I, IVAR WIDING, a citizen of the United States, and resident of Dorchester, in the county of Suffolk and State of Massachusetts, have invented an Improvement in Cement Ship Construction, of which the following description, in connection with the accompanying drawings, is a specification, like letters on the drawings representing like parts.

My present invention is an improved ship construction employing a novel, efficient and practicable method of reinforced cement ship structure.

During the present disastrous attacks on the shipping of the world by continual sinkings of ocean carrying shipping, there is a great demand for a practicable method of constructing an ocean going and seaworthy vessel permitting great speed in construction, as well as strength and cargo carrying capacity. Furthermore, the limitations in the securing of steel and wood as materials for ship construction, have created a demand for other materials. Prior to my present invention, efforts have been made to utilize cement, concrete or similar cementitious mixtures, as a material for constructing shipping, but all such prior efforts, so far as I am aware, have been expensive, and especially unsuitable for ocean going shipping or vessels which carry cargoes. I have discovered a method of construction which enables concrete, cement or the like, to be used advantageously, efficiently and expeditiously in building substantial, seaworthy, ocean going and cargo-carrying vessels, eliminating the disadvantages heretofore found in the unsuccessful efforts to build cement shipping and producing a practicable vessel very cheaply and capable of great speed in construction.

Furthermore, my improved ship construction enables me to utilize a small amount of reinforcing metal and yet to provide a perfect protecting union between the metallic and cement portions of the vessel. I prefer to so arrange the reinforcing and cement material that the metallic framework will be capable of taking up, withstanding and transmitting all strains and stresses to which a vessel is subjected, while also protecting the corner portions, edges, and the like of the concrete, particularly at stem and stern, gunwale strake and garboard portion or at either side of the keel.

Other details of construction, combinations of parts and advantages will be hereafter pointed out and claimed.

Referring to the drawings illustrating my preferred cement and iron or steel ship construction,

Figure 1 is a fragmentary mid-ship vertical section;

Fig. 2 is a plan view illustrating the stem and side construction, together with the metallic deck structure, prior to filling with cement;

Fig. 3 is a conventional side view illustrating stem and stern truss structure in detail, and a portion of the side framing prior to the application of the cement.

In the construction of my novel vessel, I utilize a metallic frame, preferably of T irons for the ribs or frames, although it will be readily understood that I may also substitute channel irons or other devices, but for the construction herein illustrated, I consider the T-form of metal preferable. The ribs or frames A are therefore herein shown as of T form, and are bent to shape in the usual manner of iron ship construction, it being readily appreciated that my novel type of reinforced concrete ship construction is readily capable of being made on any model desired. Furthermore, the steel or iron frames are of equal strength to that usually required in iron ship construction while the entire frame is greatly reinforced, strengthened and protected by the cement cover, as will be explained. Upon the T ribs A thus framed and bent I apply expanded metal B, preferably on the outer surface of the ribs, although it is also advisable in heavy construction, as illustrated in the drawings, to apply a similar layer of reinforced metal, also designated as B to the inner edge of the ribs A. Any fastening desired can be utilized to hold the expanded metal on each side of the ribs. On the outer layer of expanded metal I then apply a plurality of longitudinal metal stringers C, riveting or bolting the same through the intermediate layer of expanded metal and the T heads of the ribs A, as clearly shown in Figs. 1 and 2.

As many longitudinal stringers C to give strength to the frame can be applied as is suitable. To the metallic framework thus briefly described, I apply the coating of cement D, which is so fitted as to entirely cover the stringers C on the outside and the inner layer of expanded

metal, thus inclosing, protecting, binding, bonding and strengthening the metallic frame. Any suitable cement or concrete may be employed, but I prefer to utilize one of the types of waterproofed concrete or the concrete may be covered by a waterproofing coating.

For the deck construction I utilize similar **T** beams **A'**, using longitudinal stringers **C** and applying the cement coating **D** entirely over the same, equally protecting the deck beams. In order to give strength and seaworthiness to my ship construction, I use a heavy **I**-beam **E** for the keel, bracing the same by metallic members **F**, bolted and secured in suitable manner and all covered by the coating **D**, which coating, however, is itself protected and covered by the bottom flange of the **I**-beam **E** constituting the keel, so that no corner is here left exposed for the cement to break away or be damaged from grounding or the like. My construction also enables me to employ a plurality of bilge keels when desired. For example, I secure a channel beam **G** to the heads of the frames **A** and fit and bolt therein a bilge keel **H** which may be of wood, the arms of the channel beam **G** protecting the adjacent edge portions of the covering or planking **D** and eliminating any damage from the uneven expansion or contraction of the bilge member **G**. For internal strengthening construction I use the channel beams **I** which constitute efficient keelsons, and support the floor beams **J** and flooring **K**, a suitable central keelson **I'** being employed for greater strength in alinement with the keel **E**. The interior of my ship construction may be suitably braced, preferably utilizing midship deck beams **L**, stanchions **M**, corner braces **N** and longitudinal **T** steel deck braces, as indicated at **T**, all being suitably bolted together. At the gunwales I prefer to reinforce the angles between deck and sides by angle steel clamps **S**, and to protect the outside and corner or edge of the deck and side cement covering **D** by a similar angle steel member **Q**, running the entire length of the vessel, and bolted through to the member **S** or frames **A**, as well as being a means of carrying the pipe rail stanchions **R**.

At stem and stern I prefer to employ special steel truss constructions, which will not only reinforce and carry, hold and protect the cement covering at these points, but will also protect them by taking up and transmitting any strains or blows directly to the steel frame of the vessel. As shown in Figs. 2 and 3, the steel frame comprises a truss structure consisting of **T** irons **V**, **V** bolted to braces **W**, the side stringers **C** and the entire length of the cement **D** on the same being covered, protected and reinforced by the metallic cutwater **U**. A similar construc-

tion is illustrated at the stern post and rudder, shown in Fig. 3 at **Z**, the sheer plan herein illustrated in Fig. 3 being of the "double-ender" type, but the construction is not, of course, limited to this model.

In order to still further protect the cement sides **D** I apply one or more longitudinal reinforcing and stringer members, preferably of **T** steel, such as indicated at **P**, Fig. 1, and which protects the cement from danger by contact with wharves, lighters or the like. I may also apply a metallic reinforcing **X** to better hold and tie the two layers **B**, **B**, of expanded metal, or the like, together.

It will be appreciated that I have illustrated in the drawings the cement covering **D** of considerably greater thickness than is essential in practice. The use of a proper waterproof and toughening cement compound, will enable me to have the covering **D** of relatively less thickness than would be necessary for wooden planking in a vessel of the same tonnage, and it is, of course, feasible to utilize the cement covering only for the outer skin or planking, using wooden sheathing for the inside, similar to the flooring **K**. However, I prefer to have the cement **D** for both outer planking and inner sheathing, thus more efficiently protecting the metallic framework from damage by oxidization or other deteriorating influences, as well as solidifying the sides and frames.

My construction employs a relatively light iron or steel framework and yet one which, through its particular arrangement, spacing, joining and securing together, is capable of withstanding the strains incident to ocean going vessels and cargo-carrying shipping, which framework is immensely reinforced by the cement covering, protecting the metal throughout and in turn being protected by suitable metallic members at bow, stern, keel, bilge keels, and fender-stringers, and deck edge or gunwale, or other exposed edges or portions. The arrangement of frames **A** and longitudinal stringers **C** automatically holds the outer layer of expanded metal **B** in proper position, without relying upon insecure fastenings of said expanded metal to the frames. Furthermore, an important advantage in this construction is the economical use of metal and the fact that this construction permits of ready standardization of parts, enabling the metal frames to be quickly assembled and almost immediately the hull of the ship is completed by pouring in the cement in suitable molds spaced from the metal frame. The speed of construction possible, the economy in cost, both of material and labor, are important features and advantages in my present invention, all of which are most important at the present moment.

My invention is further described and defined in the form of claims as follows:

1. Reinforced concrete ship construction, comprising a metallic framework adapted to receive and hold a concrete covering, said framework including metallic protecting members for the corners, edges and exposed portions of said concrete, said protecting members being secured to and carried by the metallic framework.
2. Reinforced concrete ship construction, comprising a metallic framework adapted to receive and hold a concrete covering on both inner and outer surfaces, the metal framework being inclosed within said concrete, a plurality of metal guard members projecting from the metallic framework and overlapping the outer surface of the concrete covering at corners, edges, stem, stern, rail, bilge, and the like, whereby said guard members will receive and transmit strains directly to the metal framework inclosed within the concrete covering.
3. The improved method of reinforced concrete ship construction which consists in building a metallic framework with metal

truss-like timbers, securing to the same a metallic concrete receiving and holding mesh, applying to said metal framework projecting guards at a greater distance from the concrete receiving mesh than the thickness of the concrete to be applied, said guard members being adapted to overlap and protect the concrete at corners, edges, rail, keel, and the like, applying concrete to said mesh on both sides thereof entirely inclosing the metal members excepting said projecting guard members, whereby a reinforced concrete ship construction is provided with the metal framework entirely inclosed in concrete whereby the covering of concrete is protected by metal guard members carried by the inclosed framework, at corners, edges, rail, and the like.

In testimony whereof I have signed my name to this specification, in the presence of two subscribing witnesses.

IVAR WIDING.
